(57) **CLAIM**

The ornamental design for a two color mattress with a contrasting zipper strip, as shown and described.

DESCRIPTION

FIG. 1 is a perspective view of a two color mattress with a contrasting zipper strip showing our new design.

FIG. 2 is a left side view of the FIG. 1 mattress.

FIG. 3 is a right side view of the FIG. 1 mattress.

FIG. 4 is a front view of the FIG. 1 mattress.

FIG. 5 is a rear view of the FIG. 1 mattress.

FIG. 6 is a top view of the FIG. 1 mattress; and,

FIG. 7 is a bottom view of the FIG. 1 mattress.

The line shading patterns in FIGS. 1-7 are indicative of areas having different contrast and appearance between the top, middle, and bottom layers.
